UNITED STATES PATENT OFFICE.

OSCAR A. ROSS, OF BROOKLYN, NEW YORK.

AUTOMATIC TRAIN-CONTROL SYSTEM OR THE LIKE.

1,399,796.

Specification of Letters Patent. Patented Dec. 13, 1921.

Application filed April 3, 1917. Serial No. 159,523.

To all whom it may concern:

Be it known that OSCAR A. ROSS, a citizen of the United States, residing at 55 Hanson Place, borough of Brooklyn, city and State of New York, has invented a new and useful Improvement in Automatic Train-Control Systems or the like, of which the following is specification.

My invention relates particularly to that 10 division of automatic train control known as the "means for obtaining the indication from the right of way to a vehicle, or moving train" and has for its more prominent objects the production of a simpler, more 15 efficient, and more reliable means for accomplishing the result desired.

My invention relates more particularly to the class of "means for obtaining the indication from the right of way to the train" 20 known as inductive systems; namely, where the indication is given from the right of way to train by means of induced current as said train passes over one, or more of the inductors on the right of way.

As systems of this kind operate on what 25 is termed the "open circuit principle" it is necessary to check the presence of the inductors and inductive means influenced thereby, including all wires, circuits, etc., 30 involved in successful operation of such a system. One aim of my invention is to entirely check the integrity of such apparatus and circuits whereby it is assured they will be in proper place and in proper operative 35 condition at all times.

All the above and other objects sought are attained by the system which, for purposes of specific illustration, is shown in the accompanying drawings, in which:

Figure 1 is a diagrammatic view of a section of a roadway equipped with the circuits and apparatus involved in indicating inductively to a moving train, or vehicle.

Fig. 2, is also a diagrammatic view of the 45 circuits and apparatus carried by a train, or vehicle which is adapted to coöperate with the circuits and apparatus illustrated in Fig. 1.

None of the several appliances employed

in this system, are, or need be of any special, 50 or unusual form, or construction, but for a more ready understanding of the system and of its operation, a preliminary description of the devices, or appliances employed 55 may be appropriate.

Referring to Fig. 1, the rails 1—1, form a railway system of which blocks A, B, and C, are shown insulated by insulating joints 2—2. Each block is equipped with track batteries as 2A, and 2B, or their equivalent 60 and track relays as 3B, and 3C, or their equivalent. Relay 3C, is arranged to operate, or influence controlling levers 4, 5, 6, and 7, and relay 3B, levers 8, 9, 10, and 11. Signals as 12B, and 12C, are arranged at 65 the entrance to each block for indicating to trainmen the speed performance through said blocks. They are controlled in a manner well known to those skilled in the art. It is sufficient to say that if a block as C, is 70 occupied by a train as X1, that signal 12C, will be at stop as shown. Further, through influence of signal 12C, signal 12B, is made to indicate caution as shown. 14A, and 14B, are inductive devices composed of a 75 suitable magnetic core, each pole of which is secured to the opposite track rails 1—1, but suitable means such as insulation 50 may be inserted to prevent short circuiting of the track circuit. Said devices are supplied with suitable winding, as 15, as shown.

Referring to Fig. 2, X2, represents a vehicle, or train of which only one pair of wheels and axle and surrounding the axle is 85 coil 16, arranged in such a manner that any magnetic flux passing through said axle will effect or induce an electric current in said coil 16.

Also located on the vehicle is relay 17, of 90 suitable coil and core, or armature arranged to operate contact lever 18. Also located on the vehicle is relay 19, operating lever 20. Also located on the vehicle and controlling the brakes thereof is the electro-pneumatic valve EPV. This may be any of the well-known forms of train controlling devices operating to control the speed of a 95

- train, preferably of the construction as illustrated in Patent #1,072,507 granted to me Sept. 9th, 1913, and is known as the stick type, that is, after the circuit controlling the valve is opened externally, the action of the valve in operating to stop the train also maintains said circuit open at a point remote from the point where it was initially opened. Latch 46, pivoted at 49, 5 is adapted to allow armature 18 to rise but prevent its lowering to close the circuit until key operated stop 47 has been rotated sufficiently to permit latch 46 to lower below a horizontal plane. 10
- 15 Battery 21, supplies energy for the devices carried by the vehicle.

The operation of my system is as follows; normally the following track circuit is maintained:

20 *Non-indicating circuit.*

From battery 2B, wire 22, track rail 1, wire 23, relay 3B, wire 24, lever 8, wire 25, 25, coil 15, wire 27, lever 9, wire 28, rail 1, wires 29, 30, lever 7, in upper position, wire 31, returning to battery 2B. With this circuit established relay 3B, is energized and if signal 12B, were not influenced by signal 12C, it would show clear. The amount of 30 energy through relay 3B, is comparatively very small due to inherent conditions existing in a track circuit and which is known as "leakage." For example it is well known that in average track circuits only a small 35 percentage of the energy imposed upon the energy end is delivered at the relay end. Under these conditions the small amount of energy passing through inductive device, as 14A, is not sufficient to magnetize its core 40 to an extent that will induce an operative current in the cab circuit of a train as X2, while it is passing even at maximum speed, and as will be more fully hereinafter described.

45 Assume now that a train, as X1, occupies block C, thereby "shunting out" relay 3C, causing its contact levers to fall back contact as shown. Under these conditions relay 3B, is energized by the above described 50 circuit, however the coil 15, of inductive device 14B, has been added in to the circuit in the following manner; from battery 2B, wire 22, rail 1, wire 23, relay 3B, wire 24, lever 8, wires 25, 26, coil 15, of inductive device 14A, wire 27, lever 9, wire 28, upper rail 1, wire 29, lever 6, wires 45, 32, coil 15, of inductive device 14B, wire 33, lever 5, wire 34, returning to battery 2B. It will be noted that in the last named circuit the 55 integrity of windings 15, of both inductive devices 14A, and 14B, are checked, as should the circuit of either be opened, relay 3B, would be deenergized calling attention to such defect.

Assume now that a train, as X2, enters 65 block B, traveling in the direction of arrow W. Since train X1, has placed inductive device 14B in series with battery 2B, through action of relay 3C; as the wheels and axle carrying coil 16, bridge rails 1-1, of block 70 B, said battery 2B, is short circuited through said wheels and axle forming the following circuit:

Indicating track circuit.

From battery 2B, wire 22, rail 1, wheels 75 and axle of train X2, upper rail 1, wire 29, lever 6, wire 32, coil 15, of inductive device 14B, wire 33, lever 5, wire 34, to battery 2B. In this manner a large current is sent through the coil 15 of inductive device 14B, and said current increases rapidly as said train X2, approaches said inductive device 14B, and is maximum just as the coil 16 passes over coil 15. Under these conditions coil 15 of inductive device 14B, induces 80 a strong magnetic flux in its core, and as wheels and axle of train X2, pass over said inductive device a complete magnetic circuit will be formed momentarily through the core, rails, wheels and axle. This circuit is immediately broken as the wheels pass by said inductive device. In this manner a strong current is induced in coil 16, dependent upon the speed at which the said train is traveling. The path of said current is as 85 follows:

Cab operating circuit.

From coil 16, wire 35, checking relay 19, wires 36, 37, valve EPV, wire 38, lever 18, 100 wires 39, 40, cab relay 17, wire 41, returning to coil 16. It will be noted that the inductive device 14B, is placed some distance in advance of signal 12C. Assume this distance to be such that, under service 105 braking conditions the normal speed of train, as X2, will be 20 miles per hour on a decelerating curve which will permit its stopping on or before reaching signal 12C. Under these conditions the tension of spring 110 48 attached to lever 18 will be so adjusted that when a train as X1 passes over an inductive device, as 14B, at a speed in excess of 20 miles per hour, the armature 18 will be raised sufficiently to latch over latch 46. Therefore should a trainman violate the 115 caution signal 12B, and attempt to maintain maximum speed throughout block B, any speed in excess of 20 miles per hour when passing the inductive device as 14B 120 will cause relay 17 to operate and apply the emergency brakes to the train, such emergency curve being of a character which will stop said train before reaching signal 12C, even if it be traveling at maximum speed. 125

The purpose of lever 18 is to prevent any possibility of closing the circuit which it controls before said circuit is secondarily

opened by the electro-pneumatic valve EPV as it functions to apply the brakes to the train.

As the last described circuit is on the 5 open circuit principle, it becomes necessary to check the presence and integrity of all wires, apparatus, etc.; therefore the following circuit is maintained:

Cab checking circuit.

10 From battery 21, wire 42, lever 20, wires 43, 40, relay 17, wire 41, coil 16, wire 35, relay 19, wire 36, and 44, returning to battery 21. With this circuit maintained, lever 15 20 maintains a circuit to the valve EPV, as follows;

Electro-pneumatic valve circuit.

From battery 21, wire 42, lever 20, wires 20 43, 39, lever 18, wire 38, valve EPV, wires 37, 44, returning to battery 21. It will be noted this circuit can be opened through two sources, the lowering of lever 20, which would be caused by an opening of the circuit containing the coil 16, or by raising of lever 18, which would be caused by current of a substantial amount passing through relay 17. Therefore should a wire break, or should the circuit be otherwise opened, 25 relay 19 would be deenergized thereby operating valve EPV, and stopping train, calling attention to such defect in the circuit.

These and other operations, or means are applicable to my system and are referred to 35 to show its extreme flexibility and value generally as a means of obtaining the indication from the right of way to a moving train and involving a system of automatic train control.

40 The invention as I have indicated, does not depend upon the use of any specific form of apparatus for accomplishing the functions and purposes hereintofore set forth.

What I claim is:

45 1. In a system of the kind described, a vehicle, a roadway therefor divided into blocks, track circuits therefor, inductive means on said roadway included in one of said track circuits, means for disconnecting 50 each of said inductive means from one track circuit and connecting it to another and means for utilizing said inductive means.

2. In a system of automatic train control, 55 in combination: a trackway; means dividing the trackway into track circuit sections, each section including a source of current connected across the rails at one point and a relay connected across the rails at another point, the circuit of each relay including the 60 energizing coil of an inductor; means controlled by each relay for connecting the adjacent inductor in a partial circuit including a source of current and the rails of the section wherein the inductor is located whereby

an approaching train may complete said 65 partial circuit through its wheels and axle, and means for utilizing said inductor.

3. In a system of automatic train control, 70 in combination: a trackway; means dividing the trackway into track circuit sections; a relay for each section; a source of current for each section; an inductor for each section; means controlled by the relay of each section for including the relay of an adjacent section and the inductor adjacent said 75 last mentioned relay in a series circuit including the source of current.

4. In a system of automatic train control, 80 in combination: a trackway; means dividing the trackway into track circuit sections; a relay for each section; a source of current for each section; an inductor for each section; means controlled by the relay of each section for including the inductor adjacent thereto in a partially series circuit includ- 85 ing the source of current.

5. In a system of automatic train control, 90 in combination: a trackway; means dividing the trackway into track circuit sections; a source of current for each section; an in- 95 ductor for each section; a relay for each section; means controlled by the relay of each section for including the source of current adjacent the relay, the inductor adjacent the relay, the relay of the section in the rear and the inductor adjacent the relay of the section in the rear in a series circuit.

6. In a system of automatic train control, 100 in combination: a trackway; means dividing the trackway into track circuit sections; a source of current for each section; an inductor for each section; a relay for each section; means connecting the relays, the inductors and the sources of current whereby 105 a defect in the connecting means or the group of devices at any location results in rendering the inductor at the next location in the rear abnormal.

7. In a system of automatic train control, 110 in combination: a trackway; means dividing the trackway into track circuit sections; a source of current for each section; a relay for each section; an inductor for each section; means connecting the track circuit section, the source of current, the relay and the 115 inductor whereby an energization of a particular character may be caused in the inductor in the track circuit section next in the rear of a train and whereby a defect in any of the connecting means for one inductor may cause a similar energization of the inductor next in the rear thereof.

In testimony whereof, OSCAR A. Ross, has signed his name to this specification in the presence of two subscribing witnesses, this 125 14th day of March, 1917.

OSCAR A. ROSS.
